REGENERATIVE RADIO RECEIVER

Peter H. K. G. Cornelius, Eindhoven, Netherlands, assignor to N. V. Philips' Gloeilampenfabrieken, Eindhoven, Netherlands, a corporation of the Netherlands

Application April 21, 1937, Serial No. 138,132
In the Netherlands June 29, 1936

6 Claims. (Cl. 250—20)

This invention relates to a back-coupled receiving circuit arrangement and more particularly to a radio-receiving arrangement in which either grid- or diode-detection is used and in which the detector is connected in parallel to an oscillatory circuit which is undamped by back-coupling.

Such receiving arrangements have the drawback that the degree of back-coupling at which the circuit arrangement commences to oscillate with increasing back-coupling is higher than the value at which it stops oscillating with decreasing back-coupling. More particularly when receiving signals from remote transmitters it is desirable that the back-coupling should be adjusted so that the circuit arrangement just fails to oscillate. This adjustment is greatly impeded by the phenomenon referred to above. Indeed, when the back-coupling is too strong, so that the arrangement oscillates, then the back-coupling must be appreciably reduced to stop this effect.

The invention has for its object to obviate this defect and is based on the realization that the said phenomenon is caused by the fact that the damping of the oscillatory circuit connected in parallel to the detector decreases as the amplitude of the oscillations supplied to the detector increases. In fact, the diode or the grid-cathode impedance of the grid-detector constitutes a resistance which is connected in parallel to the oscillatory circuit and whose value is small (of the order of magnitude of 25,000 ohms) with small amplitudes of the oscillations supplied to the detector, whilst with increasing amplitudes this resistance increases up to a value corresponding to about half the leakage resistance of the detector (for example, of the order of magnitude of 250,000 ohms). When the circuit arrangement does not oscillate, the amplitude of the oscillations supplied to the detector is small when receiving a remote transmitting station, so that the oscillatory circuit is strongly damped and strong back-coupling must be used to cause the arrangement to oscillate. As soon as it starts oscillating the amplitude of the oscillations supplied to the detector materially increases due to which the damping of the oscillatory circuit decreases and the back-coupling must be appreciably reduced to stop self-oscillation.

According to the invention the detector is negatively biased to such a degree that the damping of the oscillatory circuit caused by the detector increases or remains approximately constant with

increasing amplitudes of the oscillations supplied to the detector.

When the detector is negatively biased to such a degree that the anode current of the diode or the grid-current of the grid-detector is cut off in the absence of oscillations, then the damping of the oscillatory circuit caused by the detector will be zero with small amplitudes, thus obtaining at any rate an increase of the damping with increasing amplitudes. However, this will involve a certain amount of distortion and for this reason it is not desirable that the negative bias should be given such a high value. In the commonly used diodes the correct value of the negative bias at which a substantially constant or a slightly increasing damping is achieved with increasing amplitude lies about between 0.5 and 0.8 volt, the extreme limits being about 0.2 and 1.3 volts.

The invention will be more clearly understood by reference to the accompanying drawing the single figure of which represents, by way of example, one form of construction thereof.

This drawing shows part of a radio-receiving circuit arrangement. The oscillations intercepted by the antenna 1 are supplied to the control grid 20 of the amplifying tube 3 through the coupling element 2 which may comprise, if desired, one or more amplification stages and/or a frequency-transformation stage. The cathode circuit of said tube comprises a resistance 4 which is shunted by a condenser 5 and serves to produce a suitable bias on grid 20. The anode circuit of the amplifying tube 3 comprises a tuned oscillatory circuit consisting of an inductance coil 6 and a condenser 7. The coil 6 is coupled with a back-coupling coil 8, whilst the voltage set up in the back-coupling coil is supplied to the control grid 20 of the tube 3 through a variable condenser 9. The oscillations occurring in the circuit 6, 7 are supplied through a condenser 10 to a detector 11 which is represented here as a diode having an anode 21 and cathode 22. Instead of a diode it is also possible to use a grid-detector. The output circuit of the diode comprises a choke coil 12 to prevent the condenser 13 from being connected in parallel to the circuit 6, 7. The audio frequency voltage occurring across the resistance 14 is supplied through the condenser 15 to an audio frequency amplifier (not shown). According to the invention the direct current circuit of the diode comprises a source of potential 16 the positive terminal of which is connected to the cathode 22, whereas its negative terminal is connected to the anode 21 so that the diode receives a

negative bias of about 0.5 to 0.8 volt. The source of potential 16 is represented as a battery, but it may have any other suitable form. For example, the direct current circuit of the diode may 5 comprise a resistance which is traversed by the anode current of one of the amplifying tubes of the receiver.

In the circuit arrangement represented in the drawing the diode 11 serves for demodulation of 10 the incoming oscillations. However it will be appreciated that the invention also includes circuit arrangements in which a diode- or grid-detector is connected in parallel to a circuit undamped by back-coupling, said detector serving to produce a 15 control voltage, for instance, for automatic volume control.

Having described my invention, what I claim as novel and desire to secure by Letters Patent is:

1. In a device of the class described, the combination of a parallel resonant circuit tunable to a desired signal frequency, a detector having a cold electrode and a heated cathode, means connecting said detector electrodes in parallel across said resonant circuit and means for maintaining 20 said cold electrode at a potential which is negative with reference to that of said heated cathode by such an amount that said detector has no damping action on said resonant circuit for small variations of voltage across said detector electrodes.
2. In a device of the class described, the combination of a parallel resonant circuit tunable to a desired signal frequency, a detector having at 25 least two electrodes comprising a cold electrode and a heated cathode, means connecting said detector electrodes in parallel across the ends of said resonant circuit and a circuit conductive to direct current connected between said detector electrodes and including a source of steady potential having a value between 0.2 volt and 1.3 volts, the positive terminal of said potential source 30 being connected to said detector cathode.

3. In a device of the class described, the combination of a parallel resonant circuit tunable to a desired signal frequency, a detector having a

cold electrode and a heated cathode, a condenser having one side connected to said cold electrode and its other side to one terminal of said resonant circuit, a circuit conductive to direct current connected between the other terminal of said resonant circuit and said heated cathode and means for maintaining said cold electrode at an average negative potential with reference to said heated cathode. 5

4. Means for receiving radio frequency signal currents comprising in combination, a parallel resonant circuit tunable to the frequency of the signal currents, a diode detector having an anode and heated cathode, a condenser having one side connected to said anode and its other side to one terminal of said resonant circuit, a connection between the other terminal of said resonant circuit and said heated cathode, and a circuit conductive to direct current connected between said anode and cathode and including the series connection 15 of a choke coil, a resistor and a source of negative potential.

5. In radio receiving apparatus including means to connect the apparatus to a source of signal energy and a detector tube and wherein means 20 are provided including a resonant circuit for connecting the first named means to said detector tube, said detector tube having an anode and a cathode, an input for said detector including means for connecting said detector electrodes in 30 parallel across said resonant circuit and means for maintaining the anode of said detector at a potential which is negative with reference to that of the cathode thereof to such a degree that the damping of the said resonant circuit caused by the 35 detector increases with increasing amplitudes of signal voltage applied to the detector input.

6. The circuit arrangement described in the next preceding claim further characterized by that the detector tube anode is maintained at a 40 negative potential of the order of 1 volt with respect to the cathode.

PETER H. K. G. CORNELIUS.
